UNITED STATES PATENT OFFICE.

PAUL HILDRETH MINER, OF BROCKTON, MASSACHUSETTS.

SIGN.

1,418,012.

Specification of Letters Patent. Patented May 30, 1922.

Application filed July 21, 1921. Serial No. 486,509.

To all whom it may concern:

Be it known that I, PAUL HILDRETH MINER, citizen of the United States, residing at Brockton, in the county of Plymouth and State of Massachusetts, have invented 5 certain new and useful Improvements in Signs, of which the following is a specification.

This invention relates to an improvement 10 in advertising signs, and more particularly to signs of the type involving moving display characters.

A primary object of the invention is to provide an attractive and effective advertising device in the form of a sign involving 15 reading matter in which only certain letters, symbols or the like, as a whole or in part, are adapted to move in such a manner that the movement or shifting of the 20 individual character will have the optical effect of causing the movement of the stationary words, letters or entire line of reading matter. While it has heretofore been proposed to move all of the individual and 25 juxtaposed letters, symbols, or the like in an advertising sign, it is pointed out that the present invention is directed particularly to the feature of having only certain 30 of the letters, symbols or the like or parts thereof move while the others remain stationary, thereby producing an entirely new and distinctive effect which differs from cases where all of the letters or their equivalent move and to cause a complete change 35 of position or otherwise affect the composition of the word or phrase.

Accordingly, the present invention proposes to provide a sign that may be readily and economically constructed to embody 40 the features referred to, and which when in operation will readily attract the observer's eye and create a distinctive impression. In this connection it is proposed to provide a sign that will be equally attractive by day 45 or by night, with the aid of suitable illumination.

With the above and other objects in view which will more readily appear as the nature of the invention is better understood, 50 the same consists in the novel construction, combination and arrangement of parts hereinafter more fully described, illustrated and claimed.

A preferred and practical illustration is

shown in the accompanying drawings, in 55 which:

Figure 1 is an elevation of a sign constructed in accordance with the present invention.

Figure 2 is a vertical sectional view taken 60 on the line 2-2 of Figure 1.

Figure 3 is a view similar to Figure 1 illustrating the change in position of certain of the letters while others remain stationary. 65

Figure 4 is an elevation of a sign wherein parts of the individual letters are adapted to move.

Figure 5 is a view similar to Figure 4 showing the parts of certain of the letters 70 in their changed positions.

Figures 6 and 7 are detail views illustrating modifications of the combination of fixed and movable characters.

Similar reference characters designate 75 corresponding parts throughout the several figures of the drawings.

In carrying the present invention into effect it is proposed to provide a suitable signboard having the desired reading or advertising matter painted or otherwise inscribed thereon, with certain of the letters, figures or other symbols making up the reading matter being mounted to individually shift or move to effect a change in position. 85

That is to say, the present improvement involves as one of its novel and distinctive features the combination of fixed and relatively movable symbols or characters which, by reason of their individual movement will 90 have the effect of causing the word or line of words to move.

To that end the signboard 1 may have painted or mounted thereon any number of fixed letters, symbols, or other characters 2 95 which may compose a word for use alone or in combination with other words as a descriptive phrase or slogan. Adjacent to the fixed or stationary letters 2 are located the movable letters 3 mounted in any suitable 100 convenient manner in the signboard to rotate as shown in Figures 1 and 2, or otherwise move or shift as suggested in Figures 6 and 7.

The said movable letters 3 may be arranged in guides 4 of convenient type in the signboard, and may be actuated or moved by any suitable mechanism as for example that

shown in Figure 2 wherein the rotatable letter 3 is provided with a pulley 5 operated by belt 6 driven by a motor 7. Obviously where two or more movable letters are used, 5 a common motion producing mechanism may be utilized to drive all of such letters by any well known mechanical expedient. In the case of rotary letters it is not essential that they be connected to rotate in unison or in 10 the same direction, as it is obviously within the scope of the present improvement for one of the letters to rotate in a clockwise direction and the other in a counter-clockwise direction with the same facility that 15 they may rotate in a common direction. In each and every embodiment of the improvement the essential and distinctive characteristic is, that a novel combination and optical effect results by mounting the fixed and 20 movable characters 2 and 3 in juxtaposition to produce the appearance of the moving characters causing the stationary characters to also move.

A further embodiment of the combination 25 of movable and fixed word-signs or characters is illustrated in Figures 4 and 5 of the drawings wherein the signboard 1^a has painted or otherwise placed thereon a word in which a part only of certain letters move 30 or shift while the remaining part of the letters remain stationary. As will be observed from inspection of the figures referred to, the letters 2^a are stationary characters but in the case of the letters "S" and "P" the 35 upper one-half of each letter is arranged to move as indicated at 3^a, thereby to produce, at intervals of rotation of the parts of the letters the effect shown in Figure 5, as will be readily understood. Obviously, the rotation of the disks 3^b carrying the movable 40 parts 3^a of the letters 2^a may be operated in any suitable and convenient manner and at different points in their cycle of rotation will form odd and unique characters which will 45 attract and impress the eye of the most casual observer.

In each of the above described forms of execution of the invention an animated sign 50 unit is provided, the same consisting of a plurality of sign or character parts in which one of the parts remains stationary while the other shifts or moves to produce the animated effect. Obviously, a sign unit may consist of a word in which certain of the 55 letters or characters remain stationary while others shift, or it may consist of a single character having a movable or shiftable part which will produce the same result.

As further illustrating the range and scope

of application of the present improvement 60 Figures 6 and 7 respectively show reciprocating and oscillating characters in combination to produce the desired novel effect.

In the case of reciprocating characters in Figure 6 the desired reciprocation may 65 be brought about by the use of a crank mechanism "C" and in the case of the oscillating characters in Figure 7 a suitable pendulum device or its equivalent "D" may be utilized.

From the foregoing it will be apparent 70 that the present improvement is directed particularly to an animated form of sign which comprises moving readable characters in combination with stationary characters constituting an intelligible and necessary part of the advertising matter, and while only certain forms of embodiment have been shown herein, it will clearly be understood that changes in the form, proportion and minor details of construction 80 may be resorted to without departing from the spirit of the invention or the scope of the appended claims.

I claim:

1. A reading sign comprising characters, 85 certain digits only of which are adapted for continuous movement.
2. In a sign, the combination of a fixed reading character and a movable reading character adapted to effect a changed position to produce the optical effect of causing the fixed character to also move, and means for continuously moving the said movable character.
3. In a sign, a legible sign board having 95 an animated reading sign unit consisting of fixed and movable letters or numerals, and means for imparting continuous motion to the movable element.
4. In a sign, a legible sign board having 100 an animated reading sign unit consisting of a plurality of reading characters and means for shifting certain of said reading characters while others remain stationary.
5. In a sign consisting of words of reading matter, the combination, in the word components of the sign, of fixed and relatively movable characters, and means causing the latter to continuously effect a change in position to produce the optical effect of 110 causing the fixed characters to also move.

In testimony whereof I hereunto affix my signature in the presence of two witnesses.

PAUL HILDRETH MINER.
